Attorney

UNITED STATES PATENT OFFICE.

DAVID W. COOPER, OF RUSTON, LOUISIANA.

ROD-JOINT.

1,209,125.

Specification of Letters Patent. Patented Dec. 19, 1916.

Application filed June 10, 1916. Serial No. 103,010.

To all whom it may concern:

Be it known that I, DAVID W. COOPER, a citizen of the United States, residing at Ruston, in the parish of Lincoln and State of Louisiana, have invented new and useful Improvements in Rod-Joints, of which the following is a specification.

My invention relates to joint connections in general and particularly to joints for drilling tools used in the drilling of wells.

The general object of the invention is to provide an improved attaching means for the drill rods and tools used in drilling wells. In the drilling of oil wells, heretofore, delays and expense have resulted from the loss of the tool head or bit, these parts becoming disconnected from the upper drill rod member and falling to the bottom of the well being drilled. In such cases the drill bit has been lost or at least costly delay has been experienced in extracting that member from the bottom of the well.

One object of the invention is to provide a socket joint so constructed that the parts connecting the drill bit to the upper connecting rod are effectively prevented from becoming unfastened and disconnected.

Another object of the invention is to provide an improved combined device for actuating the parts to be fastened together and retaining these parts in the connected position.

A further object of the invention is to provide a locking member to retain the actuating device or key in position and the combined device to operate the locking member.

The invention consists further in the novel construction and arrangement of parts together with their operation and will be more fully described and set forth in the following specification and claims, and illustrated in the accompanying drawings, in which—

Figure 1 represents an elevation showing a drill bit attached to the lower end of a drill rod, the spring lock member being the only part of the lock device visible from the exterior. Fig. 2 represents an enlarged section through the connection joint illustrating the actuating member within the drill rod and the spring means for retaining this member in position, the central plunger being drawn down to spread the expandable members within the socket flaring out within the upper end of the receiving member. Fig. 3 illustrates the lower member being an enlarged front elevation, showing the

slotted opening, the threaded cone and the expanding jaws at the upper end. Fig. 4 illustrates the device for removing and inserting the spring retaining member used over said slot. Fig. 5 represents this device as applied to the spring member, a screw member being substituted for the cam lever.

Like numerals refer to like parts.

1 represents the drill bit as connected to the lower end of a drill rod.

2 is the upper end of the bit member and is illustrated herein as being provided with the expanding jaws and centrally located plunger to operate the same, which features will be mentioned further.

3 represents the metal drill rod at the lower end of which is the enlarged portion 4 provided with the receiving socket 5. The lower end of this socket is tapered and screw threaded and converges for a portion of the way toward the inner end of the socket, but the extreme end of the socket has its side walls flared to receive the expanding jaws of the lower member. The part 2 is provided with the threaded cone 6 and has at its smaller end the members 7 arranged to expand within the flared socket of the member 4 to hold the parts together.

The central plunger 8 is provided within the member 2 and has at its upper end the cone shaped portion 9 arranged to spread the members 7 when the plunger is drawn down between them. An actuating key 10 is designed to slide through the aligned openings 11 in the member 2 and 12 in the plunger 8, the peculiar wedge shape of the part 10 drawing down the plunger 8 and spreading the parts 7. The opening 12 in the plunger must be so arranged that the part 10 has a wedging effect on the lower edge of the slot or opening to co-act therewith to draw the plunger 8 down.

Immediately adjacent the opening 11 and arranged to extend across the same, parallel thereto, is a flat spring member 13 adapted to be fastened at either end by engagement with the counter-sunk slots 14 and retain the key member 10 within the openings 11 and 12 and hence within the diameter of the drill rod connection. The member 13 is preferably arranged to lie below the exterior surface of the member 2 in a groove or channel 15 in order that engagement with the side of the well being drilled will not destroy the part 13 and consequently allow the key 10 to slide out and free the plunger 8.

The spring member 13 is arranged to be inserted and removed from the groove 15 by a device 16 which consists of the forked legs 17 adapted to rest on the spring, a central shaft 18 operating the jaws 19 which are at right angles to the legs 17, and an operating cam lever 20. The part 2 is cross channeled at 21 at right angles to the groove 15 and midway the length thereof. In removing the spring 13, the legs 17 rest on the spring near its ends, the jaws 19 are moved in the cross channel 21 and are slipped beneath the sides of the spring, and the cam member 20 is operated to lift the jaws 19 and bow the spring. As this movement advances the ends of the spring are withdrawn from the slots 14 and the spring is brought into a position to be withdrawn from the member 2. It will be obvious that the insertion of the spring 13 may be accomplished by similar use of the device 16, the bowing of the spring and the lengthening thereof into the slots 14.

Heretofore, well drilling apparatus has been subject to a most serious fault, namely the constantly recurring loss of the drill rod bits from the drill rods. This trouble has been usually traced to the type of connection used in fastening the drill rod bit to the upper member. Screw threaded connections of small pitch have constantly had the tendency to unscrew during the action of the well drilling apparatus. Various types of interlocking connections have been tried and experimented with and some form of expandable connections have been used but in all of these experience has proven that once the interlocking parts or the member expanding spreading jaws becomes loose, the drill rod bit has gradually become further loosened from the upper driving member and finally separated therefrom.

In the present invention these faults are not present, the parts being so constructed and designed that their co-operation removes the usual difficulties and trouble common to this type of apparatus. The parts 2 and 4 with their tapered ends are screw threaded together and the end of the member 2 is expanded to fill the flaring socket within the upper receiving member. The plunger 8 with the cone end 9 spreads the end of the part 2, the plunger 8 being drawn downwardly within the member 2 by the actuating key 10 which is wedge shaped to make this action possible. It will be observed here that should the parts 2 and 4 tend to rotate or unscrew from one another this movement will apply pressure to the expandable ends 7 fastened to the member 2. Hence, since the cone 9 and plunger 8 are firmly held by the wedge shaped actuating key 10, the movement just mentioned serves only to make the connection more tight. In contrast to the former structures used this invention pro-

vides for a positive connection whereas older forms of connections have had the fault of continuing to loosen if the movement once started and the parts started to unscrew.

The present invention makes use of the novel 70 spring member 13 to retain the actuating key 10 in position. This member 13 co-acts with the device 16 for its insertion and removal from the part 2. As has been explained it will be obvious that the wear and tear of 75 the drilling operation will not interfere with the operativeness of these parts, inasmuch as, both the spring and the key are in position completely within the limits of the circumference of the member 2. 80

It will be obvious from the foregoing that the parts illustrated in the lower member 2 can be constructed to operate in the upper member or that the drill rod part 4 may include the sliding shank 8 together with the 85 expandable end and the lower member might be provided with the inwardly flared socket.

From the foregoing it will be understood that the herein described invention provides a new type of drill rod connection in which 90 loss of parts and the loss of the drill bits is reduced to a minimum. It will be further understood that the invention described herein is not limited to use in well drilling machinery but may be applied successfully 95 to any apparatus in which a positive type of connection is desired.

Changes in the structure, relative location of parts, material and operation may be made without departing from the scope of 100 the invention.

What I claim is:

1. In a joint fastening, the combination of a first member having a socket flaring inwardly at its inner portion, a second member to engage the socket of said first member having an expandable end to engage the inwardly flaring portion of said socket and a transverse opening therein, expanding means for spreading said expandable end comprising a centrally located plunger provided with a transverse opening arranged to register with said first mentioned transverse opening, and unitary means for actuating said plunger arranged to pass through both 110 of said transverse openings and prevent relative movement of the parts in which they are formed.

2. In a joint fastening, the combination of a first member having a socket flaring inwardly at its inner portion, a second member to engage the socket of said first member having an expandable end to engage the inwardly flaring portion of said socket, one of said members being provided with a 120 transverse opening therein, expanding means for spreading said expandable end comprising a centrally located plunger provided with a transverse slot arranged to register with said first mentioned transverse 125 130

opening, and unitary actuating means for operating said plunger arranged to pass through said transverse opening and said transverse slot and prevent relative movement of the parts in which they are formed.

3. In a joint fastening, the combination of a first member having a socket flaring inwardly at its inner portion, a second member to engage the socket of said first member having an expandable end to engage the inwardly flaring portion of said socket, a centrally located plunger for expanding said end, and unitary means for actuating said plunger and prevent relative movement between said plunger and said first and second members.

4. In a joint fastening, the combination of a first member having a socket tapering inwardly at its outer portion and flaring inwardly at its inner portion, a second member to engage said socket tapered outwardly at its inner portion and provided with an expandable end to engage the inwardly flaring portion of said socket, one of said members being provided with a transverse opening therein, expanding means for spreading said expandable end comprising a centrally located plunger provided with a transverse opening arranged to register with said first mentioned transverse opening, and unitary actuating means for operating said plunger arranged to pass through both of said transverse openings and prevent relative movement of the parts in which they are formed.

35 5. In a joint fastening, the combination of a first member having a socket tapering inwardly at its outer portion and screw threaded thereat and flaring inwardly at its inner portion, a second member to engage said socket tapering outwardly at its inner portion and screw threaded thereat and provided with an expandable end to engage the inwardly flaring portion of said socket, one of said members being provided with a transverse opening therein, expanding means for spreading said expandable end comprising a centrally located plunger provided with a transverse opening arranged to register with said first mentioned transverse opening, and unitary actuating means for operating said plunger arranged to pass through both of said transverse openings

and prevent relative movement of the parts in which they are formed.

6. In a joint fastening, the combination of a first member having a socket flaring inwardly at its inner portion, a second member to engage the socket of said first member having an expandable end to engage the inwardly flaring portion of said socket, one of said members being provided with a transverse opening therein, expanding means for spreading said expandable end comprising a centrally located plunger provided with a transverse opening arranged to register with said first mentioned transverse opening, unitary actuating means for operating said plunger arranged to pass through both of said transverse openings and prevent relative movement of the parts in which they are formed, and means for locking said unitary actuating means in position within said openings.

7. In a joint fastening, the combination of a first member having a socket flaring inwardly at its inner portion, a second member to engage the socket of said first member having an expandable end to engage the inwardly flaring portion of said socket, one of said members being provided with a transverse opening therein, expanding means for spreading said expandable end comprising a centrally located plunger provided with a transverse opening arranged to register with said first mentioned transverse opening, unitary actuating means for operating said plunger arranged to pass through both of said transverse openings and prevent relative movement of the parts in which they are formed, and means for locking said unitary actuating means in position comprising a latch member mounted on the member provided with the transverse opening to extend across said opening and retain said unitary actuating means in position within said openings.

In testimony whereof I have hereunto set my hand in presence of two subscribing witnesses.

DAVID W. COOPER.
